Primary Examiner—Antoine Duval Davis[57] **CLAIM**

The ornamental design for a bearing for liniar movement, as shown and described.

DESCRIPTION

FIG. 1 is a perspective view of a bearing for liniar movement embodying my new design;

FIG. 2 is a front elevational view thereof, the rear elevational view being a mirror image;

FIG. 3 is a top plan view thereof;

FIG. 4 is a bottom plan view thereof;

FIG. 5 is a right side elevational view thereof, the left side elevational view being identical; and,

FIG. 6 is a partly-cut perspective view thereof.
